CLAIM

The ornamental design for a reader device, as shown and described.

DESCRIPTION

FIG. 1 is a front view of a reader device (e.g., a card reader device, such as a payment card reader device), showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top-front-left perspective view thereof;

FIG. 8 is a bottom-front-right perspective view thereof;

FIG. 9 is a top-rear-right perspective view thereof; and,

FIG. 10 is a bottom-rear-left perspective view thereof.

The shade lines show surface contour and not surface ornamentation.
